UNITED STATES PATENT OFFICE.

JOHN W. AVIS, OF ANDERSONVILLE, TENNESSEE.

WAGON-BRAKE.

SPECIFICATION forming part of Letters Patent No. 434,055, dated August 12, 1890.

Application filed May 5, 1890. Serial No. 350,671. (No model.)

To all whom it may concern:

Be it known that I, JOHN W. AVIS, a citizen of the United States, residing at Andersonville, in the county of Anderson and State 5 of Tennessee, have invented a new and useful Wagon-Brake, of which the following is a specification.

This invention relates to improvements in wagon-brakes.

10 The object of the present invention is to simplify and improve the construction of wagon-brakes and enable the same to be applied by a direct pull instead of the usual pushing of the lever away from the operator.

15 The invention consists in the construction and novel combination and arrangement of parts hereinafter fully described, illustrated in the accompanying drawings, and pointed out in the claim hereto appended.

20 In the drawings, Figure 1 is a side elevation of a vehicle provided with a brake constructed in accordance with this invention. Fig. 2 is a reverse plan view. Fig. 3 is a detail perspective view of one of the brake-blocks.

25 Referring to the accompanying drawings, 1 designates the body of a vehicle, which has journaled upon the axle 2 a rock-shaft 3, provided at one end with an upwardly-projecting arm 4 and at the opposite end with a depending arm 5. The depending arm 5 projects slightly forward and is provided with a series of perforations 6, through which passes a pin that connects the bifurcated end 7 of 30 a rod 8 to the arm 5, and the other end of the rod 8 is provided with a strap, between the ends of which is pivoted a brake-bar 9, having brake-blocks 10 at its ends arranged to engage the wheels 11, and when the rock-shaft is partially rotated the brake-blocks are 35 carried into or out of engagement with the wheels. The bar 9 is suspended from a bar 12, secured to the reach and provided at its end with depending plates 13, which are perforated and connected with eyes 14 of the 40 brake-bar by links 15, and the said brake-bar is held normally out of engagement with the wheels by a spiral spring 16, having one end centrally secured to the brake-bar and 45 its other end secured to the front end of the reach 17. The arm 4 of the rock-shaft is con-

nected by a rod 18 with the lower end of a vertically-adjustable-lever 19, fulcrumed between plates 20 and 21. The plates 20 and 21 are secured to the side of the vehicle-body 1, 55 and have pivoted between their ends nearest to the wheel the vertically-adjustable lever 19, which is provided with a series of perforations 22, and the said plates have pivoted between them at a point intermediate of their 60 ends an operating-lever that is connected to the upper end of the vertically-adjustable lever by a plate 23, having its ends bifurcated to receive the said levers. By this arrangement of parts the brake-blocks are brought 65 into engagement with the wheels by a direct pull upon the operating-lever 24, which is drawn rearward instead of being moved, as has heretofore been the case in this class of 70 brakes. The operating-lever is provided with 75 a vertical flange arranged to engage a rack-bar 25, which is secured to the side of the vehicle-body and provided with a guard or keeper 26. The outer plate 21 is provided with a curved portion 27 and an inclined portion 28, and the front ends of the plates 20 and 21 are separated by a washer, which preserves the parallelism of the parts. The upper edges of the brake-blocks are provided with adjustable scraper-plates 29, arranged 80 to remove the mud from the tires of the wheels and secured to the block by set-screws 30, the plates 29 being provided with slots 31.

It will readily be seen that the wagon-brake is simple and inexpensive in construction, 85 capable of direct operation, and is adapted to be applied by a rearward pull upon the operating-lever.

What I claim is—

In a wagon-brake, the combination of the 90 rock-shaft provided at one end with a depending arm 5, adjustably connected with a spring-actuated brake-bar, and having at its other end an upwardly-projecting arm 4, the plates arranged parallel with each other and 95 secured to the side of the vehicle-body, the outer plate having the curved portion 27 and the inclined portion 28, the vertically-adjustable lever 19, pivoted between the rear ends of the plate, the operating-lever 24, pivoted intermediate of the ends of the plates, the rod 18, connecting the lower end of the vertically- 100

adjustable lever to the arm 4 of the rock-shaft, the plate 23, having its ends connecting the upper end of the vertically-adjustable lever with the operating-lever, and the rack-bar having the guard or keeper, substantially as described.

5 In testimony that I claim the foregoing as

my own I have hereto affixed my signature in the presence of two witnesses.

JOHN W. AVIS.
